UNITED STATES PATENT OFFICE.

GEORGE E. WHRITENOUR, OF SLOATSBURG, NEW YORK.

PAPER BAG AND THE LIKE.

1,164,688.

Specification of Letters Patent. Patented Dec. 21, 1915.

Application filed February 17, 1915. Serial No. 8,732.

To all whom it may concern:

Be it known that I, GEORGE E. WHRITENOUR, a citizen of the United States, residing at Sloatsburg, in the county of Rockland and State of New York, have invented certain new and useful Improvements in Paper Bags and the like, of which the following is a specification.

This invention relates to paper bags or sacks and similar containers, and it consists, in a bag or sack having a novel means whereby to retain its mouth securely closed without the employment of cord or other separate securing means, as will be made clearly to appear by this specification in view of the accompanying drawing, wherein,

Figure 1 is a plan of the improved bag, folded; Fig. 2 is a longitudinal central sectional view thereof; and, Fig. 3 a transverse sectional view of the bag in the mid portion thereof.

"a" in the drawings is a paper-bag or sack of the well-known so-called square-bottom type. To one side of this bag or sack I secure a paper-piece "h" having two parallel lines of perforations "i", one near each side edge of the piece. This paper-piece is secured to the side of the bag by gluing or pasting it along the side margins thereof wholly outside of the two lines of perforations, as at "h", Fig. 2, leaving the intermediate portion unattached to the side of the bag. It is preferred that the piece be also pasted or glued to the side of the bag across its lower end portion as at "g". Said intermediate portion may then be adapted as a flap, in the way to be explained by drawing downwardly and outwardly on its upper end, thus ripping the said intermediate portion clear of the outlying or marginal portions of the paper piece, which remain adhering to the side of the bag. By pasting or gluing the lower end portion of the flap, as well as the longitudinal marginal portions, to the bag, the flap is prevented from being entirely separated from the bag when ripped from the paper piece "h". At the upper end the flap-forming intermediate portion of the paper piece is preferably cut away from the marginal portions of the piece, as indicated at "j", thus leaving said end free so that it may be easily grasped by the thumb and forefinger for starting the ripping out of the

flap, and so as to insure the ripping following the lines of perforation.

Upon the bag receiving its contents and its mouth being folded down tightly to form a compact package, the flap having been formed by ripping down the intermediate portion of the piece "h" is extended over the folded mouth portion of the bag, and, being drawn more or less tightly around the same, is made to adhere to the opposite side of the bag by adhesive "k" applied to the inside of the free end of the flap. It is obvious that this operation may be accomplished in a way much more expeditious than with the use of cord or the like and that when it is completed a neatly formed compact package is the result.

I do not wish to be limited to the precise details herein shown and described, what I claim being:

1. A bag of the class described having face to face with the outer surface of one side thereof a piece of sheet material having spaced rip-lines extending longitudinally of the bag, said piece being secured to the bag outwardly of each rip-line and detached therefrom between the rip-lines for a suitable distance downwardly, whereby the part of said piece between the rip-lines may be ripped downwardly to form a flap adapted to be folded over the folded-over mouth-portion of the bag.

2. A bag of the class described having face to face with the outer surface of one side thereof a piece of sheet material having spaced rip-lines extending longitudinally of the bag, said piece being secured to the bag outwardly of each rip-line and detached therefrom between the rip-lines for a suitable distance downwardly, whereby the part of said piece between the rip-lines may be ripped downwardly to form a flap adapted to be folded over the folded-over mouth-portion of the bag, and adhesive means to secure the free-end portion of said flap to the opposite side of the bag.

In testimony whereof I affix my signature in presence of two witnesses.

GEORGE E. WHRITENOUR.

Witnesses:

JOHN W. STEWART,
